ULTRASONIC GENERATOR

Eliot Huntington Harris, New York, N. Y.

Application September 28, 1949, Serial No. 118,323

12 Claims. (Cl. 177—7)

1

This invention relates to the generation of compressional waves or vibrations having a frequency above the highest frequency of response for the human ear. More particularly, it relates to improved apparatus for generating such ultrasonic waves.

One of the objects of this invention is to provide an improved generator of ultrasonic waves which is simple, practical and durable in operation. Another object is to provide apparatus of the above character which may be manufactured from readily available inexpensive materials without excessive labor costs. A further object is to provide apparatus of the above character capable of generating compression waves with high efficiency and a wide range of displacement amplitudes. It is another object to provide apparatus of the above character capable of generating such waves over a wide range of frequencies without critical or complicated adjustment of the apparatus. Another object is to provide such apparatus in which the frequency of the waves may be varied during operation. Other objects will be in part obvious and in part pointed out hereinafter.

The invention accordingly consists in the features of construction, combinations of elements, and arrangements of parts, as will be exemplified in the structure to be hereinafter described, and the scope of the application which will be indicated in the following claims.

Pressure waves created in air, within a particular range of frequencies, are audible to the human ear. However, as the frequency of these waves is increased, the human ear becomes less responsive to the waves, and, accordingly, above 15 or 20 thousand cycles per second, the waves become inaudible. However, sound waves much higher in frequency can be generated, and their existence can be detected by thermal means, striation methods, piezoelectric pick-up and other physical devices. Such longitudinal waves of frequency above the audible hearing range are called ultrasonic waves.

It has been found that such high frequency waves in either gas or liquid medium are useful for many purposes, both in production and in research. However, generation in air of ultrasonants having appreciable energy and with variable frequency over wide frequency bands has been a very difficult laboratory problem and has hampered the advancement of scientific knowledge of the effects produced by such wave motions.

Experiments, starting as early as 1833, utiliz-

ing specially designed whistles, minute tuning forks, spark discharges, or various other laboratory mechanisms indicated that these waves had unusual and interesting characteristics, and that such waves might well be useful for certain commercial applications if satisfactory generating equipment could be constructed. Some of the fields in which experiments have been conducted relate to emulsification, cavitation, coagulation, and underwater object detection.

Other fields, still to be explored but in which promising indications have been obtained, include the effects on crystallization and grain formation, degassing operations, fog clearance, dispersion of metals in liquids, biological studies, including the treatment of viable cells, sterilization, destruction of enzymes, killing of insects, dispersion of paint pigments, polymerization and depolymerization, catalyzation, therapy, and many others.

It has been found that particular effects can be achieved with high efficiency if certain "critical" frequencies are employed. These critical frequencies may depend on environmental conditions and may shift during a particular process, making it necessary to change the frequency of these generated waves in order to successfully complete the desired process. In some applications, a certain minimum power is required to achieve the desired result and below this power level no substantial effects may be observed.

Accordingly, there have been many attempts to produce apparatus capable of generating such ultrasonic waves. Many kinds and varieties of generators have been developed, but none would produce all frequencies over a band that extended into the higher reaches of the sonic spectrum.

For example, piezoelectric crystals, such as quartz, have the property of converting electrical vibrations into mechanical vibrations. There are several disadvantages of such a crystal arrangement, for example, such crystals are relatively expensive, and the size may be prohibitive at the lower frequencies. Moreover, the efficiency of operation is relatively low and the amount of power which may be applied to the crystal is definitely limited, and if the power should exceed this value, the crystal may be fractured. In many instances, the most important disadvantage is that the frequency range over which the crystal may be operated efficiently is very narrow, so that such a device is relatively unsuitable for applications which require variations in frequency.

Other devices, such as magnetostriction units,

sirens, whistles, are limited in range to frequencies below those most desirable for many applications.

In the accompanying drawings, in which is shown one of the various possible embodiments of this invention:

Figure 1 is an elevational view of an ultrasonic generator constructed in accordance with the present invention;

Figure 2 is an enlarged sectional view taken on the line 2—2 of Figure 1;

Figure 3 is an enlarged sectional view taken on the line 3—3 of Figure 1;

Figure 4 is an enlarged sectional view taken on the line 4—4 of Figure 1;

Figure 5 is an enlarged partial section taken on the line 5—5 of Figure 1;

Figure 6 is a sectional view taken on the line 6—6 of Figure 1;

Figure 7 is a sectional view taken on the line 7—7 of Figure 1;

Figure 8 is a sectional view taken on the line 8—8 of Figure 1; and

Figure 9 is a schematic diagram representing apparatus suitable for applying electrical energy to the ultrasonic generator.

Similar reference characters refer to similar parts throughout the several views of the drawings.

As shown in the drawings, a piston 2 of magnetic material (Figures 1 and 8) is mounted between a pair of driving coils 4 and 6. The piston 2 is in the shape of a disc, or may have any other desired configuration, and may be formed, for example, of an alloy of nickel, silicon, and iron, so that it has desirable magnetic properties, and, in order that it may respond to the desired frequency range, is of relatively small dimensions; for example, it may have a diameter of one centimeter and a thickness of three ten-thousandths of an inch.

In order that the piston 2 may vibrate as freely as possible, and that it may operate efficiently over a wide frequency range without serious resonance effects, it is mounted on a non-magnetic sheet or net 8 of material having suitable resilient or flexing characteristics and which is non-elastic within the amplitude of movement when in oscillation. For example, good results have been obtained using a net formed of nylon thread, such as is used for the manufacture of ladies' hairnets, or it may be formed of nylon cloth. The sheet 8 is clamped along two opposite edges (Figure 4) and is maintained under suitable tension by a spring arrangement described below.

One edge of the sheet 8 is secured to a beveled surface of a tensioning member 12 (Figure 4) by an adjacent beveled surface of a clamping piece 14 (Figure 3), which fits within tension member 12 and is secured thereto by screws 16 which pass through clamping piece 14 into the tensioning member 12. The sheet 8 thus is secured at one end along its entire length so that even tensioning may be applied to the entire edge of the sheet. The opposite edge of sheet 8 is secured (in a similar manner to frame member 18 (Figures 1 and 4) between the opposing beveled faces of frame member 18 and a clamping piece 22 by screws 24 in substantially the same manner as that described above. The other two edges 26 and 28 (Figure 1) of the membrane 8 are unsupported and are free along their entire length from the surrounding structure.

In order that the desired tension may be main-

tained upon the membrane 8, the tensioning member 12 is slidably supported on two rods, generally indicated at 32 and 34, which extend between frame member 18 and a second frame member 36, to which they are secured, respectively, by nuts 38 and 42 and lock nuts 44 and 46, respectively. Rods 32 and 34 are provided with threaded portions 48 and 52, respectively, which pass through clearance openings near the ends of tensioning member 12. In order to provide the desired tension on sheet 8, compression springs 54 and 56 are mounted on rods 32 and 34, respectively, and abut against tensioning member 12 and are held in compression by a pair of knurled thumb nuts 58 and 62 which are in threaded engagement with rods 32 and 34, respectively.

It is apparent that as the thumb nuts 58 and 62 are rotated so as to approach clamping bar 12, the pressure exerted by springs 54 and 56 increases and, thus, the sheet 8 is placed under increasing tension. It is also apparent that these thumb nuts 58 and 62 may be adjusted individually so that uniform tension may be applied throughout the membrane 8.

In order that the tensioning adjustments may be approximately reset if the structure is dismantled, a pair of scales 64 and 66 are provided, which are secured to tensioning member 12 by screws 68 and extend outwardly over thumb screws 58 and 62, respectively. Suitable calibrations are inscribed on the members.

It is to be understood that the sheet 8 is for the purpose of supporting the piston 2 between the coils 4 and 6, and that, desirably, the movement of piston 2 is not restrained elastically by the supporting sheet 8, so that resonant effects are substantially eliminated over the operating range.

In order to vibrate the piston 2 (Figure 8) over the entire range of frequencies, the coils 4 and 6 are arranged to alternately attract the piston 2 in opposite direction. The coil 4 comprises a coil form or spool 72 which supports a winding 74. The coil form 72 is constructed of insulating material as, for example, ceramic or similar material, and the winding 74 is a low impedance winding, the axis of which extends through the piston 2. The coil 6, mounted on the opposite side of the piston 2, comprises a spool 76 formed of similar material and a winding 78. The spool 76 is similar to coil form 72 except that an opening 82 is always provided centrally therethrough. The winding 78 is similar in all respects to the winding 74.

With this arrangement, when alternating currents having the proper phase relationship are caused to flow through windings 74 and 78, a magnetic field is created which tends to urge piston 2 first in one direction and then in the opposite direction. The movement of piston 2 creates the ultrasonic vibrations. The vibrations are transmitted to the desired area through the opening 82 in the spool 76.

The coil form 72 is supported on a preferably non-metallic bridge 84 which is supported at each end by U-shaped non-magnetic members 86 and 86A, by means of screws 88 which extend through slots 90.

Coil form 76 is supported on a bridge member 92 which is provided with a circular opening 94 coincident with the opening 82 in coil form 76. The bridge member 92 is supported at the ends by means of U-shaped members 96 and 96A to which it is secured by bolts 98.

In order that the generation of the ultrasonic waves can be accomplished efficiently, it is important that the coil forms 72 and 76 be placed as close to the piston 2 as is possible without the sheet 8 or the piston 2 making contact with the coil forms during any part of the vibratory energization.

In order to accomplish this, the members 86 and 96 are supported adjustably at their outer ends on two screw members 102 and 104, respectively (Figure 5). The member 86 is in threaded engagement with screw 102, which is supported rotatably in a U-shaped yoke 106, and which is provided with a knurled adjustment knob 108. The support 96 is in threaded engagement with screw member 104, which is supported rotatably in the opposite end of yoke 106, and which is provided with a similar knurled adjustment knob 112. The innermost portions 116 and 118 of screw members 102 and 104 are of reduced diameter and are seated rotatably in suitable recessed openings in opposite sides of an abutment member 122.

In order to anchor screw members 102 and 104 in place, snap rings 124 and 126 are provided in suitable grooves in screws 102 and 104, respectively.

Thus, by rotation of knob 108, the support 86 and the coil 4 may be moved laterally with respect to the piston 2 so that the desired close spacing may be achieved readily. The outer end of member 86A is supported in a similar manner so that the opposite end of the structure which supports coil 6 may be moved in a similar manner by adjustment of a knob 108A (Figures 1 and 2), and the structure which supports coil 6 may be adjusted by knobs 112 and 112A. In order to facilitate these adjustments, a mirror 132 (Figure 1) can be mounted, for example, on rod 32 by means of a bracket 134 (Figure 7) which is fitted advantageously with a swivel connection 136 so that the angular direction of the mirror face may be adjusted readily. A similar mirror (not shown) may be attached to rod 34 in a diagonal position so that, by placing a small light source directed downward on the second mirror on the opposite side of the coils 4 and 6, the spacing between the coils may be adjusted readily by observing in the mirror 132 the passage of light between coil form 72 and the piston 2 and between the spool 76 and the opposite side of the piston 2.

For the purpose of centering the coils 4 and 6 over and under the piston 2, slots 90 are provided in the bridge members 84 and 92, whereby the bridge members 84 and 92 may be moved laterally with respect to the U-shaped members 86, 86A, 96 and 96A when screws 88 and 98 are loosened (Figure 8).

Longitudinal adjustment of the coils 4 and 6 may be obtained for the purpose of further centering over and under piston 2 by loosening screws 114 (Figure 5) and moving them within the limits of the holes 115, thus obtaining longitudinal adjustment by the movement of yoke 106.

It is desirable that the coils 4 and 6 be coaxial and centered with respect to piston 2. It is advantageous to adjust coil 4 so that the space between piston 2 and the near face of coil 4 is a multiple of half wave lengths. This adjustment may be easily located by observing the output intensity on any indicating device, such as the sensitive flame, or a metering device if greatest efficiency is desired. If coil 4 is provided with center hole similar to coil 6, then it is sufficient

that the clearances between coils 4 and 6 and the piston 2 be small. It is further advantageous for the sheets 8 to be adjusted with sufficient tension to hold the piston 2 in position but also loose enough so that the tension does not exercise a restoring force on the piston within its displacement amplitude.

In order to energize windings 74 and 78, a source of oscillating electrical energy is used. The preferred arrangement is to provide alternations to windings 74 and 78 such that there is a 90° lead or lag in the phase relationship of the oscillations between the two windings. Thus, there is produced four peak impulses to move piston 2 during each cycle of the driving current. These will occur from alternate directions and cause the piston 2 to complete two cycles for each cycle of the driving current. Other arrangements may be employed. A square wave form in which one half of the wave is suppressed in winding 74 and a similar condition established in the winding 78 with the additional requirement that the suppression in one winding corresponds to the peak in the other will produce an excellent force diagram for movement of the piston 2. In this case, one cycle of the driving current produces one cycle of the piston movement. However, for a variable frequency, such a circuit as last described becomes extremely complex. The simplest circuit provides a sinusoidal wave form of the same phase to the two windings 74 and 78. In this case, it is necessary to have the direction of winding in one driving coil opposite to the winding of the other. It is also necessary to magnetize the piston 2 in the direction of its thickness. Thus, due to the polarity of the piston 2, there is a simultaneous repulsive-attractive force acting on the piston in one direction and then in the other direction as the current reverses. This produces one cycle of the piston for one cycle of the current. The residual magnetism of piston 2, when polarized in the direction of its thickness, which is the axial direction, is low and the rate of decay is too high for long usage. Maintaining an electrical charge on the piston introduces the additional inertia of the conductor and offers the danger of a spark which might ignite combustible gases present in certain applications. For these and other obvious reasons, the preferred arrangement calls for a 90° phase relationship between the oscillations in the windings 74 and 78.

In order to obtain a variable frequency oscillating current in the windings 74 and 78, any one of the available types of circuits may be used. For example, the circuit diagrammatically indicated in Figure 9 has been found suitable. Alternating house service at A and B (Figure 9) serves the power pack 140. The incident high frequency can be conveniently supplied by a commercial signal generator 138. The signal is then amplified by the wide band amplifier 142. The output is coupled with the power transformer 144. The secondary 146 is preferably at reduced voltage, as, for example, 25 volts with a primary potential of 2800 volts. In this way, a small number of turns will be called for in the windings 74 and 78.

In order to obtain the 90° phase shift between the driving coils 74 and 78, a phasing network may be placed in the driving circuit parallel to the windings 74 and 78 and consisting of a resistance 152 and a condenser 148 in series. It is advisable to center tap this circuit to a connection between windings 74 and 78.

The location of this phasing network is not

essential in the preferred circuit. For example, the phase shift may be located at the output from the variable frequency generator 138 and the amplifier 142 will be designed for parallel amplification of the two circuits. The output will be coupled to power transformer 144 and a twin (not shown). The secondaries will be connected directly with their respective windings 14 and 78. This arrangement is more economical since each amplifier is for one half the total power. However, it is more sensitive to changes in frequency. Both arrangements described require that changes be made in the value of the components, particularly the phasing network, as the frequency is changed. The arrangement shown in Figure 9 proved suitable over small bands, such as 50 kc. to 80 kc., without changes. Convenient switches are therefore provided to allow for different frequency bands. Still another arrangement would call for a center tap in the secondary 146 with junction between the two windings 74 and 78. In this case, resistance 152 is placed in the lead from secondary 146B to winding 78 and condenser 148 is placed in the lead from secondary 146A to winding 74. With this arrangement, the wave form at the windings is apt to be affected by every small change in frequency. This would call for a rebalance of the system after each small frequency change.

It is to be understood that the wave form applied to the coils 4 and 6 may be varied in accordance with a particular application and, for example, may be a square wave, a sawtooth, or other wave form.

It is seen readily that a highly efficient generator of supersonants has been provided, which is operable over an extremely wide frequency range and which may be constructed easily and economically. It is to be understood that various modifications may be made to adapt the structure to various applications and uses and that certain features of the invention may sometimes be utilized without a corresponding use of other features, all within the spirit and scope of the present invention as set forth in the following claims.

I claim:

1. In apparatus for generating ultrasonic vibrations, a translating device comprising a supporting frame, a piston of magnetic material, a sheet of resilient non-magnetic material supported by said frame, said piston being secured to and supported by said sheet for free transverse movement therewith, a first and second coil with axial opening for egress of the ultrasonic vibrations supported by said frame on opposite sides of said piston for vibrating said piston and positioned so that the axes of said coils pass through said piston, and a source of first and second periodic out-of-phase currents connected to said coils for causing said piston to move alternately toward said first and second coils thereby to generate ultrasonic vibrations.

2. Apparatus as described in claim 1 wherein said first and second currents are substantially ninety degrees out-of-phase.

3. In apparatus for generating ultrasonic vibrations, a translating device comprising a supporting frame, a piston of magnetic substance, non-metallic non-magnetic supporting material secured to said frame, said piston being secured to and supported by said material so as to be free for limited elastically unrestrained transverse movement, a first and a second coil having

an axial opening for the ultrasonic vibrations supported by said frame on opposite sides of said piston for vibrating said piston, and a source of first and second periodic out-of-phase currents connected respectively to said first and second coils for causing said piston to move as a unit in a transverse direction alternately toward said first and second coils thereby to generate ultrasonic vibrations.

4. In apparatus for generating ultrasonic vibrations, a translating device comprising a supporting frame, a piston of magnetic material, a net of flexible non-magnetic material supported by said frame, said piston being secured to and supported by said net for limited free transverse movement therewith, a first and a second coil supported by said frame on opposite sides of said piston for vibrating said piston, one of said coils having an axial opening substantially the area of said piston, a source of alternating current, a phase-shifting network connected to said source and to said coils for causing alternating current to flow in each of said coils, the current through said first coil lagging by substantially ninety degrees the current in said second coil.

5. In apparatus for generating ultrasonic vibrations, a translating device comprising a supporting frame, a piston of magnetic material, a sheet of resilient non-magnetic material supported by said frame, said piston being supported for limited free transverse movement by said sheet, a first and second coil supported by said frame adjacent said piston and on opposite sides of said sheet for vibrating said piston, said second coil having a longitudinal opening therethrough in alignment with said piston for transmitting the ultrasonic vibrations, and a source of first and second periodic out-of-phase currents connected respectively to said first and second coils for causing said piston to generate ultrasonic vibrations.

6. Apparatus as described in claim 5 including manual screw adjustments for regulating the position of said coils relative to said piston.

7. In apparatus for generating ultra-sonic vibrations, a translating device comprising a supporting frame, a piston of magnetic material, a sheet of flexible non-magnetic material supported by said frame, said piston being supported by said sheet and positioned thereon at a point substantially removed from points at which said sheet is supported, a first and second coil supported by said frame adjacent said piston and positioned on opposite sides of said sheet for vibrating said piston, said second coil having a longitudinal opening therethrough in alignment with said piston for transmitting the ultrasonic vibrations, and a source of first and second periodic out-of phase currents connected respectively to said first and second coils for causing said piston thereby to generate ultrasonic vibrations.

8. In apparatus for generating ultrasonic vibrations, a translating device comprising a supporting frame, a piston of magnetic material, a fixed and a movable clamp secured to said frame, screw adjusting means for varying the position of said movable clamp, a sheet of flexible non-magnetic material supported at one end by said movable clamp and at the opposite end by said fixed clamp, said piston being supported by said sheet for substantially free transverse movement, first and second oppositely disposed coils mounted adjacent said piston for vibrating said piston as a unit relative to said coils, at least one of said coils having

a longitudinal opening for egress of the ultrasonic wave motion and a source of first and second alternating out-of-phase currents connected respectively to said first and second coils for producing periodically varying magnetic fields to which said piston is responsive.

9. Apparatus as claimed in claim 8 including adjustment screws for adjusting individually the positions of said coils relative to said piston.

10. In apparatus for generating ultrasonic vibrations, a translating device comprising a supporting frame, a small thin disc of magnetic material, a fixed and a movable clamp secured to said frame, screw adjusting means for varying the position of said movable clamp, a strip of flexible non-magnetic open mesh supported at one end by said movable clamp and at the opposite end by said fixed clamp, said disc being supported by said mesh for substantially free transverse movement, first and second coils with axial openings mounted adjacent said disc for vibrating said disc as a unit relative to said coils, separate screw adjustments for varying the position of said coils with respect to said disc and a source of first and second periodic out-of-phase currents connected respectively to said first and second coils for producing periodic magnetic fields to which said disc is responsive.

11. In apparatus for generating ultrasonic vibrations, a translating device comprising a supporting frame, a piston of magnetic material, a strip of resilient non-magnetic material supported by said frame, said piston being supported by said strip for free transverse movement therewith, first and second supporting bridges adjustably supported by said frame on opposite sides of said strip, first and second oppositely disposed coils supported respectively by said first and second bridges adjacent said piston, said coils having longitudinal openings for passage of the

5 wave motion, and a source of periodic out-of-phase currents of ultrasonic frequency connected to said coils for causing said piston to vibrate transversely as a unit, thereby to generate ultrasonic vibrations.

12. In apparatus for generating ultrasonic vibrations, a translating device comprising a supporting frame, a piston of magnetic material, a fixed and a movable clamp secured to said frame, screw adjusting means for varying the position of said movable clamp, a strip of resilient non-magnetic material supported at one end by said movable clamp and at the opposite end by said fixed clamp, said piston being supported by said strip for substantially free transverse movement, first and second supporting bridges adjustably supported by said frame on opposite sides of said strip, first and second oppositely disposed coils supported respectively by said first and second bridges adjacent said piston for vibrating said piston, at least one of said coils having an axial opening for egress of the wave motion and a source of first and second alternating out-of-phase currents connected respectively to said first and second coils for producing periodically varying magnetic fields to which said piston is responsive.
